UNITED STATES PATENT OFFICE.

HERMANN SACK, OF PHILADELPHIA, PENNSYLVANIA.

FOOT-WARMER.

SPECIFICATION forming part of Letters Patent No. 325,116, dated August 25, 1885.

Application filed October 18, 1884. (No model.)

To all whom it may concern:

Be it known that I, HERMANN SACK, a citizen of the United States, residing in the city and county of Philadelphia, State of Pennsylvania, have invented a new and useful Improvement in Foot-Stools and Foot-Warmers, which improvement is fully set forth in the following specification and accompanying drawings, in which—

10 Figure 1 represents a side elevation of a foot-stool and foot-warmer embodying my invention. Fig. 2 represents a top or plan view thereof. Fig. 3 represents a vertical section thereof. Fig. 4 represents a view of a detached portion.

15 Similar letters of reference indicate corresponding parts in the several figures.

My invention consists of a combined foot-stool and foot-warmer formed of detachable parts, and provided with means for warming the heels as well as the other parts of the feet, as will be hereinafter fully set forth.

Referring to the drawings, A represents a base, on which is removably supported a 25 box, B, and C represents a foot-stool, which is removably supported on said box B. The base A has a flange, a, which circumscribes the box B, whereby the latter is prevented from lateral displacement, and the frame of 30 the stool C has a flange, b, for preventing shifting of the foot-stool, it being noticed that the latter has a foot-supporting portion, c, and a heel-supporting cross-bar, d, both suitably upholstered, the stool being set at a slope 35 or inclination for properly sustaining the feet thereon.

Within the lower part of the box B is a pan or case, D, for containing hot water, it being seen that the upper wall of said pan 40 forms a rest for the feet when the latter are inserted in the box B to be warmed.

The portion of the box above the pan D is lined with sheepskin, felt, fur, &c., in the form of pockets E, which are warmed by heat from 45 the pan D, and adapted to receive the main portion of the feet.

The box is provided with a door, F, which closes the pockets E, and to the same are connected curved pieces G, adapted to 50 close the heels of the feet, and when not in use to be folded within the pockets E. Springs H, formed of rubber bands or coiled

wire, are attached to the door F and the sides of the box in order to hold the pieces G when in use against the heels, and when not in use 55 to draw the same within the pockets E.

The door F is made in two parts, the pieces G being attached to the lower part thereof, so that when the warmer is in use the upper part of the door remains open to provide a 60 space for the legs. J represents a door connected with the box for covering and uncov- 65 ering the pan D.

It will be seen that when the parts are in position shown in Figs. 1 and 2 a foot-stool is 65 provided, and when the pan is filled with hot water and the door F is opened the heel-pieces G may be drawn out and the feet then inserted in the pockets E. The pieces G then close around the heels, and thus all parts of the feet 70 may be nicely warmed.

The foot-stool may be removed should it be desired to use the warmer in a carriage, sleigh, &c., and the base A may also be removed for pur- 75 poses of transportation, storage, &c.

Having thus described my invention, what I claim as new, and desire to secure by Letters Patent, is—

1. A combined foot stool and warmer consisting of a box with a warming-pan therein, so 80 a detachable base, and a detachable foot-stool, substantially as and for the purpose set forth.

2. A foot-warmer provided with pockets 85 adapted to receive the main portion of the feet, and separate pieces connected with the sides of the pockets by springs for closing around the heels thereof, substantially as and for the purpose set forth.

3. A foot-warmer, in combination with a 90 foot-rest sustained thereon, provided with a heel-supporting cross-bar, substantially as and for the purpose set forth.

4. A combined foot stool and warmer consisting of a box having within the same a 95 warming-pan and pockets, the latter being above the former, a base, and a foot-stool pro- 90 vided with a heel-rest, substantially as and for the purpose set forth.

HERMANN SACK.
